CLAIM

The ornamental design for a cable terminal, as shown and described.

DESCRIPTION

FIG. 1 is a perspective view of a cable terminal showing our new design;

FIG. 2 is a top plan view thereof;

FIG. 3 is a bottom plan view thereof;

FIG. 4 is a front elevational view thereof;

FIG. 5 is a right side elevational view thereof, a left side elevational view thereof being a mirror image;

FIG. 6 is a rear elevational view thereof;

FIG. 7 is a perspective view of another embodiment of a cable terminal showing our new design, a top plan view thereof being shown in FIG. 2;

FIG. 8 is a bottom plan view thereof;

FIG. 9 is a front elevational view thereof;

FIG. 10 is a right side elevational view thereof; a left side elevational view thereof being a mirror image; and,

FIG. 11 is a rear elevational view thereof.
